W. P. ARON

ELECTRICAL SAFETY RAZOR

Filed Nov. 20, 1925

William P. Aron

INVENTOR.

BY

G.C. Waldrop

ATTORNEY.

UNITED STATES PATENT OFFICE.

WILLIAM P. ARON, OF DALLAS, TEXAS, ASSIGNOR, BY DIRECT AND MESNE ASSIGNMENTS, TO ARON ELECTRIC RAZOR COMPANY, OF NEWARK, NEW JERSEY.

ELECTRICAL SAFETY RAZOR.

Application filed November 20, 1925. Serial No. 70,255.

This invention relates to razors, and more particularly to electrically operated razors of the safety variety, and the primary object of the invention comprehends a means by which a reciprocal action is imparted to the cutting element of the razor by electrical energy, whereby to obtain a greater degree of cutting efficiency by effecting a mechanical lateral action as well as the vertical action of the blade, by manual manipulation of the instrument over the surface of the skin.

The invention further provides a razor of such form and shape as to afford a convenient hand hold for efficient manipulation to obtain effective results, as well as to afford a neat appearing instrument of such character as to enable the same to be readily assembled and dismantled for cleaning and other purposes.

Of particular importance among the objects of the invention, is the one piece safety guard, forming a part of the razor structure and which permits of the minute edge of the cutting element to contact with the flesh without danger of abrasion or injury thereto.

With the foregoing and other objects and advantages in view, the invention has particular reference to certain novel features of construction and arrangement of parts, which will reveal themselves as the description proceeds, taken in connection with the accompanying drawings, wherein:

Figure 1 represents a side elevational view of the invention assembled.

Figure 2 is a similar view in front elevation.

Figure 3 is an elevational view of the invention in vertical cross section.

Figure 4 is a rear view of the invention in vertical elevation with portions cut away showing the manner of securing the safety guard thereon.

Figure 5 is a detail view of the safety guard in perspective, and

Figure 6 is a detail view of the preferred form of blade used in connection with the razor herein.

In proceeding more in detail, the invention consists primarily of a hollow handle portion 1, composed of any suitable non-

conducting material. Within the hollow portion of the handle is disposed a small coil 2 of the usual 110 volt variety, to which the wires 3 are applied as illustrated, and through which the instrument is furnished with the required electrical current.

The handle portion 1 is interiorly threaded at its upper end to receive a cover 4, which latter is in turn interiorly threaded to receive a small tubular member 5, having a shoulder thereon and acting as a housing through which a plunger 6 reciprocates. In contact with the coil 2, a small metal disc 7 is threaded upon the end of the plunger 6, and between the said disc and cover 4, a small expansion spring 8 is interposed to aid in maintaining the disc in intermittent contact with the coil, as in Figure 3.

Upon the upper end of the plunger 6 and integral therewith is a small cap 9, arranged to conformably fit over the upper end of the tubular member 5, while a small spring 10 surrounds the said member 5 to engage with the cap 9 and an adjusting nut 11 directly therebelow, threadedly movable upon the body of the tubular member 5. It will be observed by reference to Figure 3 of the drawings that the urge of the spring 8 is adverse to that of the spring 10, situated interiorly of the handle 1, such arrangement adding materially to the sensitiveness of the plunger 6.

A shield 12, the construction of which member is detailed in Figure 5, is provided, which obviates the necessity of employing a conforming member to cover the blade, commonly used in the construction of safety razors generally. This shield comprises a member preferably as shown, one end of which is bent upon itself and turned outwardly at right angles to the shield proper, at which point it is apertured to receive the tubular member 5, the shoulder of the latter holding the shield from displacement when screwed into position within the cover 4.

Particularly in Figures 2 and 5, it will be observed that the shield 12 is longitudinally channeled to receive a slide 13, in which the latter is adapted to actuate longitudinally of the shield, such actuation being imparted

thereto through a pin 14, extending through a slot 15 longitudinally cut in the shield 12, and engaging in an indentation or aperture in the cap 9. Position of the slide as described is maintained by a bifurcated clip 16, engaging in slots cut into opposing sides of the pin 14, and is so constructed as to springingly bear against the under side of the shield 12.

- 10 A double edged blade 17, illustrated in detail in Figure 6 is provided, and is equipped with oppositely directed, semi-circular apertures as shown, which latter are arranged to receive the protuberances 19, 15 disposed upon either end of the slide 13. These apertures are indicated on the drawing by the numeral 18, and are so arranged as to hold the blade in position upon the protuberances 19 and to positively align the 20 blade with the undulated edges of the shield 12, see Figure 5, thereby forming a guard and permitting only a limited portion of the blade to be exposed to the skin when in operation. In Figure 3, the protuberances 25 are shown as being tapered inwardly toward the base thereof, whereby one of the apertures of the blade 17 may receive one of the protuberances, while the opposite end of the blade is firmly pressed down upon the 30 opposite protuberance to snap the blade into rigid position thereon.

In assembling the instrument for use, the coil 2 is properly connected up with the wires 3, after which it is placed within the 35 body 1. The tubular member 5 is threaded into the cover 4 and the adjusting nut 11 is mounted in its proper place thereon. The small spring 10 is then mounted upon the tubular member 5, and the plunger 6 inserted therethrough, thence through the 40 cover 4. The spring 8 is then placed around the plunger 6, after which the disc 7 is threaded upon the end of the plunger as shown. After this assemblage is completed, 45 the cover 4 is threaded into the handle portion 1, whereby the disc 7 will normally contact with the coil 2.

In assembling the blade and shield, the 50 slide member 13 is placed within the channel in the shield 12 in such a manner as to permit the pin 14 to enter the slot 15, and its extremity to lie within the indentation or aperture in the cap 9, as shown. The bifurcated clip 16 is pressed into position upon 55 the pin to prevent dislocation thereof and to hold the slide in perfect alignment with the channel and to effect its smooth movement therein. The blade 17 is then mounted as previously set forth to complete the 60 assembly.

When electrical current is established within the coil 2, the intermittent magnetic contact of the disc 7 with the coil obviously imparts a minute reciprocal action to the 65 plunger 6, which, in turn, by reason of the

pin 14, moves the blade 17 at a high velocity longitudinally through the channel of the shield 12. The adjustment to alter the stroke of the blade 17 is made through the nut 11, which moves upon the threads 70 arranged upon the periphery of the tubular member 5, and upon which the spring 10 rests, as previously described.

Certain elements employed herein have been described as being the preferred form 75 to complete the structure, but it should be understood that equivalent parts may be substituted in carrying out the invention to obtain the best results, without departing from the spirit or intent of the invention as 80 set forth in the following claims:

1. An electrical razor comprising a hollow handle and a shield removably supported thereon having longitudinally disposed undulated edges; a blade reciprocally mounted on said shield; a coil within said hollow handle; a plunger mounted in normal contact with said coil, the latter arranged to magnetically impart intermittent reciprocal action to said plunger, a cap on the end of 90 said plunger and means impinging said cap to transmit said action to said blade.

2. An electrical safety razor including a hollow handle portion and a fluted shield removably supported thereon, a member 95 movable longitudinally in the flute of said shield, having an integral pin extending through said shield; a blade reciprocally supported on said member; a plunger mounted rearwardly of said shield having connection with said pin, and means within said handle to impart alternating action to said plunger to effect movement of said blade.

3. An electrical safety razor including a hollow handle member and a blade carrying shield supported thereon; a blade reciprocally mounted on said shield, a plunger disposed behind said shield, a cap removably supported upon the end of said plunger; an intermediate connection between said cap and blade mounting means and within said handle member to impart magnetic reciprocal movement to said plunger.

4. An electrical safety razor including a hollow handle and a blade carrying shield supported thereon having a longitudinally disposed apertured channel therein; a slide movable in said channel; a pin mounted on said slide and extending through the aperture in said channel; a bifurcated clip springingly engaging said pin and arranged to impinge said shield to hold the pin; a blade mounted upon said slide and arranged to be affected by the movement of the latter; means to engage the protruding end of said pin; means to impart alternative reciprocal action to said pin engaging means to movably affect said pin, and means to adjust the movement thereby transmitted.

5. An electrical safety razor including a hollow handle member and a blade shield removably attached thereto; a blade detachably mounted upon said shield; a magnetic coil mounted within said handle member; a plunger adjacent thereto and arranged to be reciprocated thereby; a cap on said plunger, a pin intermediate said cap and blade mounting disposed to impart the action of said plunger to the blade, and means below said 10 cap to adjust the movement thereby transmitted.

In testimony whereof I affix my signature.

WILLIAM P. ARON.
